US00D597937S

(12) **United States Design Patent**
Haw et al.

(10) **Patent No.:** **US D597,937 S**
(45) **Date of Patent:** **** Aug. 11, 2009**

(54) **CHARGING DEVICE**

(75) Inventors: **Brandon Haw**, London (GB); **Gregory Carlyon Simmons**, Brighton (GB); **Calvey Kenneth Taylor-Haw**, Hove (GB)

(73) Assignee: **Elektromotive Limited**, Falmer, Brighton (GB)

(**) Term: **14 Years**

(21) Appl. No.: **29/313,222**

(22) Filed: **Dec. 17, 2008**

Related U.S. Application Data

(63) Continuation of application No. 29/270,275, filed on Dec. 19, 2006, now abandoned.

(30) **Foreign Application Priority Data**

Jun. 19, 2006 (EM) 000547161

(51) **LOC (9) Cl.** **13-02**

(52) **U.S. Cl.** **D13/107**

(58) **Field of Classification Search** D13/107–110, D13/118–119, 139.5, 184; D14/251, 253, D14/432, 434; 320/107–115

See application file for complete search history.

(57) **CLAIM**

The ornamental design for charging device, as shown and described.

DESCRIPTION

FIG. 1 is a side view thereof;

FIG. 2 is a front view thereof;

FIG. 3 is a side view thereof;

FIG. 4 is a top plan view thereof; and,

FIG. 5 is a perspective view of a charging device showing our new design.

1 Claim, 5 Drawing Sheets
